C. GIRTON

ADJUSTING DEVICE FOR TYPEWRITERS

Filed July 29, 1924

FIG. 1

FIG. 2.

INVENTOR
Cameron Girton

BY
White Post Evans
his ATTORNEY'S

UNITED STATES PATENT OFFICE

CAMERON GIRTON, OF BERKELEY, CALIFORNIA.

ADJUSTING DEVICE FOR TYPEWRITERS.

Application filed July 29, 1924. Serial No. 728,861.

To all whom it may concern:

Be it known that I, CAMERON GIRTON, a citizen of the United States, and a resident of the city of Berkeley, in the county of Alameda and State of California, have invented a new and useful Adjusting Device for Typewriters, of which the following is a specification.

This invention relates to mechanical writing machines, such as typewriters, in which characters are typed in succession by the operation of a key-board upon a sheet held on a relatively movable platen or roller. More particularly, my invention relates to an improved form of adjusting device for the sheet upon which the printing is accomplished.

In mechanical writing machines of this character, such as typewriters or adding machines, it is necessary that the sheet upon which the writing is to appear be firmly held to the platen or roller. This is usually accomplished by the aid of spring clamps which may be released at will by the operator to adjust the sheet in the machine, whenever it is necessary for the purpose of making corrections or the like. Prior to my invention, the adjustment of the sheet was accomplished by releasing these clamps and by moving the sheets manually with respect to the platen or roller to the desired extent. It is evident that this is laborious and inefficient to perform accurate adjustment. It is one of the objects of my invention, therefore, to make it possible to adjust the sheet with respect to the writing elements of the machine in a more efficient and simple manner.

My invention is especially useful where a sheet of written matter must be corrected and it is necessary to position the sheet accurately with respect to the parts which carry the printing type, so that when the printing is accomplished the letter or character will be properly positioned with respect to the remainder of the written matter on the sheet. Since each character on the ordinary writing machine occupies a space of about one eighth of an inch, it is seen that this adjustment should be of a comparatively fine order to preserve the neat appearance of the writing.

I accomplish these objects of my invention by providing a platen or roller which may be accurately adjusted to any desired extent upon its carrying member, such as a shaft or the like. It is therefore, another object of my invention to provide a platen or roller which is adjustably mounted on its support.

My invention possesses other advantageous features, some of which with the foregoing, will be set forth at length in the following description, where I shall outline in full that form of the invention which I have selected for illustration in the drawings accompanying and forming part of the present specification. Although I have shown in the drawings but one form of my invention I do not desire to be limited thereto, since the invention as defined in the claims, may be embodied in other forms also.

Referring to the drawings:

Figure 1 is a front elevational view of a typewriting machine embodying my invention, the roller being shown in section; and

Fig. 2 is an enlarged sectional view of the roller, some of the length of the roller being broken away to permit the use of a larger scale.

In Fig. 1 a standard form of typewriter is shown, having a frame 11, which appropriately supports the key mechanism and keys 12, and also supports a sliding frame 16, in which there are appropriate bearings 13 and 14 for a roller or platen 15. The moving frame 16 is advanced step by step as the keys 12 are operated, in a manner now well understood. The roller 15 in this instance is shown as hollow, and supported on a shaft 10 in a manner to be hereinafter described. This shaft also carries a ratchet wheel 17, used to rotate the roller step by step at the beginning of each line of type.

The sheet 18 upon which the printing is to appear, is guided around the roller by the aid of the guide 23 supported on the movable carriage 16 and near the back of the roller 15. A knurled button 19 is provided near one end of shaft 10, for the purpose of manually rotating the platen 15 whenever it is necessary or desirable to do so.

As thus far described, the machine differs in no wise from the standard typewriter construction. As is usual the platen or roller 15

is provided with an outer flexible covering or layer 20, such as rubber, beneath which a rigid cylinder 21 is provided. The shaft 10 passes through the end flanges 22 and 23 which close the ends of the cylinder 21.

In order to permit the making of corrections or for other purposes, it is sometimes necessary that the sheet 18 be adjusted relative to the carriage 16 in the direction of movement thereof. This result could be obtained by shifting the sheet 18 laterally on the roller 15, while this roller is stationary. This method of procedure is, however, cumbersome, and in order to obviate it, I preferably arrange the device in such a way that the platen 15 with the sheet 18 may be adjusted relatively to the moving frame 16. For this purpose the platen 15 is not rigidly attached to the shaft 10, but instead, it is slidably mounted thereon as by the aid of the slot and key connection 24 at its left hand end. To make possible a fine adjustment of the roller 15 with respect to the shaft 10, a hollow screw 25 is rotatably mounted near the right hand end of the roller on the shaft 10, and is threaded into the flange 23. This screw has a head 27 which is knurled to facilitate manual operation. It is also provided with a screw 26 passing radially through the head 27 and engaging a groove 32 in the shaft 10 in order to prevent the axial movement of the screw 25 with respect to the shaft 10.

The unthreaded portion of screw 25 serves as a journal which is supported in the right hand bearing 14 on the moving frame 16. As thus far described, it is evident that rotation of screw 25 will cause a corresponding axial movement of the roller 15 with respect to the shaft 10. While this rotation is accomplished one hand of the operator may be used to hold the paper 18 firmly to the roller 15, while the spring clamps holding the paper are released. This longitudinal adjustment of sheet 18 with respect to the frame 16 may be made as fine as desired by providing a sufficiently small pitched thread on screw 25. For convenience the head 27 of the screw 25 is located outside of the frame 16 so that it may readily be manipulated by the operator. However, other forms of longitudinal adjustment may be provided for the roller 15, the present form being one that is preferable from the standpoint of simplicity.

Of course, under normal operation, the screw 25 is permitted to remain stationary. In order to prevent accidental rotation of the screw 25, I preferably arranged some kind of a frictional brake which acts on the screw 25. In this instance I have shown a spring pressed plunger 28 engaging the face of the head 27 and guided in a sleeve 29 fastened in the knurled button 19. The pressure exerted by this means on the face of

head 27 is made sufficient to provide a frictional force preventing accidental rotation of the screw 25. This force may be adjusted by the aid of a screw 30 threaded into the end of the sleeve 29, and operating on the free end of the coil spring 31 interposed between the screw 30 and the plunger 28. It is also possible to provide stops to limit the extent of adjustment of the roller.

Although I have disclosed my invention as applied to a typewriting machine, it is evident that it is as applicable to other types of mechanical writing machines such as adding machines, in which there is a relatively movable carriage supporting a sheet upon which characters are to be printed by the operation of keys such as 12, which impart to the carriage a step by step motion. The manner of use of the invention is evident from the foregoing description. In order to space the sheet 18 accurately so as to print a character in a desired position, it is merely necessary to rotate the screw 25 by the aid of the knurled head 27 until the proper horizontal adjustment is obtained. Variations in the adjustment of the roller 15 also serves to vary the positions thereon where the type bars strike the roller, and in this way the wear is well equalized. Since the type bars thus do not hit continually at the same spots, a longer useful life of the roller is assured.

I claim:

1. In a printing device, a type printing mechanism, a frame movable step by step relative to the mechanism, for moving a sheet into proper position to be operated on by the mechanism, a roller for supporting the sheet, a shaft supporting the roller on the frame and means for adjusting the roller axially on the shaft, comprising a hollow screw mounted coaxially on the shaft and threadedly engaging the roller.

2. In a printing device, a type printing mechanism, a frame movable step by step relative to the mechanism, for moving the sheet into proper position to be operated on by the mechanism, a roller for supporting the sheet, a shaft supporting the roller on the frame, and means for adjusting the roller axially on the shaft, comprising a hollow screw mounted coaxially on the shaft and threadedly engaging the roller, and means for restraining the rotation of the screw.

3. In a printing device, a type printing mechanism, a frame movable step by step relative to the mechanism, for moving a sheet into proper position to be operated on by the mechanism, a shaft carried by the frame, a hollow screw rotatably mounted on the shaft, and axially restrained thereon, a roller mounted coaxially with the shaft and threadedly engaged by the screw, and bearing support for one end of the shaft and for the screw.

4. In a printing device, a type printing

mechanism, a frame movable step by step relative to the mechanism, for moving the sheet into proper position to be operated on by the mechanism, a roller for supporting the sheet, a shaft supporting the roller on the frame, means for adjusting the roller axially on the shaft comprising a hollow screw mounted coaxially on the shaft and threadedly engaging the roller and a friction brake for restraining the rotation of the screw. ¹⁰ In testimony whereof, I have hereunto set my hand.

CAMERON GIRTON.
